UNITED STATES PATENT OFFICE.

ALFRED SMALLWOOD, OF LONDON, ENGLAND.

FURNACE.

1,421,852.

Specification of Letters Patent. Patented July 4, 1922.

Application filed March 8, 1920. Serial No. 364,266.

To all whom it may concern:

Be it known that I, ALFRED SMALLWOOD, a subject of the Kingdom of Great Britain, residing at 42 Hargrave Park, Highgate, 5 London, N., in the county of Middlesex, England, metallurgist, have invented certain new and useful Improvements in or Relating to Furnaces, of which the following is a specification.

10 This invention comprises certain improvements in or relating to furnaces, suitable for the heating or treatment of plates and the like.

According to the present invention, the 15 heat is adapted to be admitted to the working chamber by a series of ports which advantageously are individually regulable, and another series of ports is provided for admitting to the working chamber advantageously in proximity to the ports first mentioned, air which has been heated in a recuperator located below the working chamber.

In order that this invention may be clearly understood and readily carried into practice, reference may be had to the appended explanatory drawings, upon which:—

Figure 1 is a sectional side elevation of a furnace according to the present invention.

30 Figure 2 is a sectional end elevation of the furnace shown in Figure 1.

Figure 3 is a sectional plan of the furnace shown in Figures 1 and 2, the plane of section being on line 1—2 of Figure 2.

35 Figure 4 is a sectional plan of the furnace shown in Figures 1, 2 and 3, the plane of section being on line 3—4 of Figure 2.

In a convenient embodiment of the present invention, the working chamber *a* is located in the upper part of the furnace, and below the said working chamber a longitudinal green gas flue *b* is provided. Gas generators *c*, *c* are in communication with this green gas flue at one extremity. From the 40 said green gas flue on both sides, ports or 45 passages *d* extend upwardly from the working chamber at intervals along the length of the latter.

Below the green gas flue a recuperator 50 system is provided by which the air for combustion is adapted to be heated by the waste furnace gases from the working chamber. This recuperator system may comprise a series of longitudinal flues *e* to which the 55 waste gas descends from one extremity of

the working chamber by way of ports *f* and a chamber *g*, and from the other extremities of which the waste gas passes to the stack by way of a common transverse flue *h*. Adjacent to such other end a cold air flue *i* is 60 provided from which air ascends to intermediate air flues *j* extending longitudinally between the waste gas recuperator flues *e*. At the other extremity of the recuperator system, i. e. the extremity remote from the gas 65 producer, these air flues descend into a common transverse hot air flue *k* from which on each side of the furnace an air flue *l*, *l* extends longitudinally on either side of the recuperator system. From each of these air 70 flues last mentioned branch flues *m* or ports extend upwardly at intervals along the length of the furnace and terminate in ports admitting to the working chamber at intervals along the length of the same in proximity to, and preferably above, the gas admission ports *d*. Each ascending branch may feed two ports *n*, for which purpose it may be of T-form in elevation. The air 75 ports as well as the gas ports being individually regulable, more or less heat can be imparted to any part of the working chamber, and the actual combustion may advantageously take place within the working chamber upon the admixture of the recuperated 80 air with the green gas admitted by the gas ports leading from the main gas flue located between the working chamber and the recuperator system. In this main gas flue the gas is adapted to flow towards the charging 85 door of the furnace, which thereby tends to prevent ingress of cold air therethrough. Gas ingress ports *o* may be located across the end of the furnace remote from the charging door, said gas ports *o* being adapted to extend from the end of the green gas flue *b*. The air flues *l* are extended to positions *p* on each side of the gas producers, at 90 which positions they extend upwardly as shown at Figure 3. At an appropriate level lateral flues *q* extend from the flues *p* and terminate in air ingress ports *r* admitting to the extremity of the working chamber in proximity to the gas ingress ports *o*.

What I claim as my invention and desire 105 to secure by Letters Patent is:—

A furnace, including a gas generator, a green gas flue communicating with said gas generators, a working chamber above said flue, a recuperator below said flue, a plural- 110

ity of conduits extending from said flue to
said working chamber and including individ-
ually regulable ports, discharge means
connecting said working chamber and re-
5 cuperator, air flues located on each side of
the furnace and passing through said re-
cuperator, and flues each extending verti-

cally from said air flues to pairs of individu-
ally regulable ports admitting to the work-
ing chamber.

10

In witness whereof I have hereunto set
my hand.

ALFRED SMALLWOOD.
